UNITED STATES PATENT OFFICE.

WALTER A. JONES, OF COLUMBUS, OHIO.

FORMER BLOCK.

Application filed December 1, 1924. Serial No. 753,239.

To all whom it may concern:

Be it known that I, WALTER A. JONES, a citizen of the United States, residing at Columbus, in the county of Franklin and State of Ohio, have invented a new and useful Former Block, of which the following is a specification.

This invention is a refractory former block for use in drawing glass in sheet form.

One of the objects of the invention is to provide a former block which may be constructed of material buoyant with respect to glass, said block being capable of partial submergence in the molten glass, in such manner that a sheet may be drawn from that portion of the bath which lies immediately over the block. A further object is to provide a block of the character described which will be so shaped as to facilitate the formation of the sheet as it is being drawn. A further object is to provide a block of the character mentioned, provided with temperature controlling means located near the top thereof, so as to control or modify the temperature of that portion of the glass which immediately overlies the block, and which is normally drawn into the body of a sheet.

The invention will be hereinafter fully set forth and particularly pointed out in the claims.

In the accompanying drawing:

Figure 1 is a side elevation illustrating a former block constructed in accordance with the invention. Figure 2 is a longitudinal sectional view on the line 2—2, Figure 1, showing the block partially submerged in the molten glass. Figures 3 and 4 are views of different forms of temperature regulating means.

Referring to the drawing, 10 designates a former block constructed of refractory clay or suitable heat resisting alloy metal, the material of which it is constructed being such that the block will float upon molten glass. Said block is approximately rectangular in cross section, the top surface being convexedly rounded, the curvature of said surface being transverse to the longitudinal median line of the block. The said top surface is also inclined upwardly, as indicated at 12, contiguous to both ends of the block.

If desired the block may be provided with a longitudinal channel 13, in its upper surface, said channel forming a seat for the reception of a conduit 14, into which may be

introduced a temperature-modifying fluid such as water or air. The temperature-modifying fluid may be hot or cold, as the conditions involved in the shaping of a glass sheet may require.

In Figure 4 the block is illustrated as provided with a plurality of conduits 15 and 16, through which temperature controlling media may be caused to circulate in any desired manner.

In operation the block 10 is caused to float upon the bath of molten glass at the drawing point, but at the same time is partially submerged by suitable means well-known in the art. Referring to Figure 2, the molten glass is indicated at G, and the sheet in course of drawing is indicated at S.

When the molten glass is in proper condition, a bait of any desired or well-known type is placed in contact with that portion of the molten bath which lies immediately over the rounded top surface of the block 10, and the draw proceeds in a well-known manner. It will be noted that an approximately shallow body of molten glass is maintained immediately above the body 10, the temperature of which is influenced by the block 10, and it is from this shallow portion of the glass bath that the sheet is drawn, new glass flowing over the top surface of the block as the drawing progresses. Said shallow portion S, by reason of the shape of block 10, is deeper at the sides than along the longitudinal medial line of the block, which is the line of draw. By means of this arrangement the glass is maintained at a proper drawing temperature during the drawing operation, and the progress of drawing is greatly facilitated. By providing the end of the top surface 11 with raised portions 12, the edges of the sheet are formed from glass which is somewhat cooler than the rest of the bath, and for this reason the edges will set more quickly than the rest of the sheet area, thereby maintaining the shape and preventing "drawing in" of the edges as the sheet is formed.

If for any reason it should be desired to vary the temperature of the shallow portion of the glass from which the sheet is drawn, either by heating or chilling, a block of either of the forms of Figures 3 or 4 may be employed. If the type of block of Figure 3 is employed, it will be noted that by passing a cooling medium through the conduit 14, the glass may be materially chilled at

the drawing point, or if it is found that the temperature should be raised, a heating medium is introduced instead of cooling medium. The type illustrated in Figure 4 may 5 be employed in the same way, but by reason of the increased volume of the combined temperature control passages 15 and 16, it is possible to obtain a more delicate response 10 to changes in temperatures in the glass at the drawing point.

The advantages of the invention will be readily understood by those skilled in the art to which it belongs. It will be particularly noted that a former block of simple 15 construction is provided, capable of being partially submerged in molten glass, and so shaped as to greatly facilitate the speed at which the glass sheet may be drawn. An important advantage is that means are provided 20 for controlling the temperature of the glass directly at the point of draw. It is to be understood that when the block 10 is constructed of heat-resisting alloy, it will not float upon the molten glass but must be 25 supported in suitable manner in the desired submerged position.

Having thus explained the nature of the invention and described an operative manner of constructing and using the same, 30 although without attempting to set forth all of the forms in which it may be made, or all of the forms of its use, what is claimed is:—

1. A former block of the character described comprising a solid block of material buoyant with respect to molten glass, and capable of being submerged in a glass bath, 35 said block having a convex top surface, the curvature of which is transverse to the longitudinal median line of the block.

2. A former block of the character described comprising a solid block of material buoyant with respect to molten glass and capable of being submerged in a glass bath, 45 said block having a convex top surface, the curvature of which is transverse to the longitudinal median line of the block, said block being thicker at its ends than at the portions intermediate therebetween.

3. A former block of the character described comprising a solid block of material buoyant with respect to molten glass and capable of being submerged in a glass bath, 50 said block having a convex top surface, the curvature of which is transverse to the longitudinal median line of the block,

said top surface being also inclined upwardly contiguous to the ends of the block.

4. A former block of the character described comprising a solid block of material 60 buoyant with respect to molten glass and capable of being submerged in a glass bath, said block having a convex top surface, the curvature of which is transverse to the longitudinal median line of the block, 65 said block having temperature controlling means located contiguous to the said top surface.

5. A former block of the character described comprising a solid block of material 70 buoyant with respect to molten glass and capable of being submerged in a glass bath, said block having a convex top surface, the curvature of which is transverse to the longitudinal median line of the block, and temperature controlling conduits extending longitudinally of the block contiguous to the top surface thereof.

6. The method of drawing sheet glass which comprises partially submerging a 80 temperature control element in a molten bath of glass, and drawing a sheet from that portion of the glass which lies immediately above the temperature controlling element.

7. The method of drawing sheet glass 85 which comprises producing an elongated relatively shallow portion in a glass bath from which the sheet may be drawn, said shallow portion being deeper at the sides than at the middle, regulating the temperature of said shallow portion, and drawing a sheet from the middle of said shallow portion.

8. The method of drawing glass sheets comprising providing an elongated relatively 95 shallow portion in a bath of molten glass, said shallow portion being deeper at the middle than at the ends, and regulating the temperature of the shallow portion of the bath as the sheet is drawn.

9. The method of drawing sheet glass comprising partially submerging an elongated temperature regulating element into a molten glass bath to provide a correspondingly shaped shallow overlying portion of molten glass, drawing the sheet from said overlying portion, and varying the temperature of said overlying portion.

In testimony whereof I have hereunto set my hand.

WALTER A. JONES.
